UNITED STATES PATENT OFFICE.

JAMES A. SHEPARD, OF MONTOUR FALLS, NEW YORK.

ELEVATED TRACKWAY.

1,115,029.

Specification of Letters Patent. Patented Oct. 27, 1914.

Application filed February 7, 1914. Serial No. 817,342.

To all whom it may concern:

Be it known that I, JAMES A. SHEPARD, a citizen of the United States, and resident of Montour Falls, county of Schuyler, State of New York, have invented certain new and useful Improvements in Elevated Trackways, of which the following is a specification.

My invention relates to that type of rail-way in which the trackage is suspended at intervals from the ceiling of a room or carried by a series of overhead supports and is adapted to span the space intervening between the points of support and to carry a car and load suspended underneath the trackage.

Heretofore it has been common practice to construct a track from steel channel or I-beams which beams are well adapted to bridge the space between the points of support, and the projecting lower flange of which also affords a suitable bearing or track for the car wheels. The quality of the steel of the ordinary beam is such that the lower flange will not for any great length of time withstand the abrasive action of the car wheels. The beam almost immediately begins to wear causing it to lose its strength and soon it has to be entirely replaced while all the parts except its lower flange are substantially as strong as when new.

It is one of the objects of my invention to apply renewable wearing strips or members to the lower flange of the beam in such a manner that they can be removed and replaced when worn out at the least possible expense, the beam meanwhile having sustained no injury or wear.

Another object of my invention is to arrange these wearing strips so that they are completely supported by the beam upon which they are placed and may therefore be made of a hard quality of steel which will resist for a long period the abrasion of the car wheels.

The foregoing and other objects and novel features of the invention will be apparent from the following description, taken in connection with the drawings, in which:

Figure 1 is a sectional view of a track embodying my invention and showing in dotted lines the outline of a part of a car and car wheels supported on the track.

Fig. 2 is a sectional view of a trackway embodying my invention in which the track is arranged on one side of the beam only.

Fig. 3 is a sectional view of a track supported on a beam made by riveting structural shapes together. Fig. 4 is a sectional view of a railway embodying my invention in which the spreader bar is omitted. Fig. 5 is a sectional view of a modification in which the spreader members are supported on the flange of the beam and support the trackway. Fig. 6 is a sectional view of still another modification in which the invention is applied to a channel beam which supports the trackway comprising one rail only.

Referring to the drawings, 10 designates a beam for supporting a trackway, which beam may be supported from the ceiling by riveting the upper flange 11 thereto or it may be supported at its ends on the walls of the building, or on other suitable supports so that the beam will bridge the intervening space and form a support for the trackway. As illustrated the beam may be either a solid rolled I-beam, a built-up I-beam as shown in Fig. 3, a channel as shown in Fig. 6, or other suitable section 80 provided with one or more flanges 12 at its lower end to engage the rail 13 or rails 13 and 14 of the trackway.

Referring to Figs. 1, 3 and 4, the rails 13 and 14 extending longitudinally of the beam 85 and applied to the projecting lower flanges 12, may be shaped like the ordinary T-rail as shown in Fig. 1 or some suitable modification may be employed such as the L-rails shown in Fig. 3 and the channel rails shown 90 in Fig. 4. The essential feature of the rail or rails employed to reinforce the edge of the flange of the beam is that it shall interlock with the beam or flange in such a manner that the loaded wheels passing over 95 the track will be supported directly by the inclined or upper surface 12' of the beam flange and only reduced or secondary stresses shall occur in the rails or the members which co-operate with the beam and 100 rails to support the latter in their proper relation to the beam.

In order to support the rails on the flange or flanges of a beam, I provide a spreader member 15 at intervals along the track 105 which in Figs. 1 and 3 is shown as of substantially the same length as the width of the lower flange and fits in between the webs of the T-rails, the heads of which fit against the inclined upper surfaces 12', 12' of the flange. The spreader member 15 in Figs. 1 and 3 has a longitudinal opening therein to

receive the shank of a bolt 16 the head of which engages against the outside of the web or vertical part 30 of a rail while the shank extends through the web or vertical part of 5 the rail or other coöperating member and the threaded end receives a nut to secure the spreader member in place and to draw the parts tightly together so that the bottom of the head of the rail will rest flush on the inclined surface or transmit its weight directly to the beam without undergoing any strains itself. The coöperating spreader members 15 and bolts 16 are distributed at suitable intervals along the length of the 10 track and hold the rails firmly in position without being subjected to more than a fraction of the loads carried by the rails, said loads being almost entirely taken directly by the supporting beam.

20 In the construction shown in Fig. 4 the spreader is dispensed with, the channel rails 13 and 14 being so constructed that their lower flanges 13' and 14' are spaced from the lower flange of the beam a distance 15 slightly in excess of the diameter of the bolt 16 so that the body of the latter will act as a spreader and resist the reaction caused by tightening the bolt.

In Fig. 5 I have shown a modification in 30 which the relation of the rails to the flange of the supporting beam and the spreader members is reversed whereby the flange of the supporting beam acts as a spreader and also as a support and the spreaders 17 and 35 18 fit in between the surface 19 of the flange of the beam and the under surface 20 of the head of the rail 13. The member 18 thereby acts as a filler between the rail and flange of the beam, serving to locate the rails at a 40 higher elevation relative to the beam and at the same time retaining the fit with the rail directly supported by interlocking with the flange of the beam. Each filler member 17 and 18 has a longitudinal opening there- 45 through to receive the through bolt 21 which extends through a hole in the web of the beam 10 and may be tightened up to draw the parts into close contact whereby the rails transmit their load directly to the flange of 50 the beam.

In Figs. 2 and 6 the invention has been applied to a trackway consisting of a single rail and the spreader member 22 is formed so as to support the one rail in proper relation to the flange of the beam. The spreader member 22 for this purpose is formed with an offset hook 23 at its end opposite the end engaging the web of the rail. In Fig. 2 the bent end of the hook 23 fits over the 55 flange of the I-beam opposite the flange engaged by the rail while in the construction shown in Fig. 6 the hook is formed so that its bent end will fit into a hole 24 punched into the web of the beam. In both instances 60 the offset end 23 of the spreader member 22

engages and hooks over the flange at the end opposite the end of the flange engaging the rail. The spreader members in both instances are provided with longitudinal openings to receive bolts 25 by means of which 70 bolts the spreaders as well as the rails may be drawn into close contact with the flange and secure the parts together.

By the construction shown in Figs. 1, 2, 3, 4, and 5, the rails are securely attached 75 to the beam without the expense of punching holes in the beam or the care required to accurately space all holes so as to secure perfect register between the holes in the rails and the corresponding holes in the beam. 80 In all forms, the original cost of construction is greatly reduced and the renewal of the rails, while not nearly so frequently necessary as the renewal of the beams heretofore, is greatly facilitated. Furthermore, 85 the whole structure is rendered more safe because no part relied upon for carrying the load between the supports is subject to wear and consequent loss of strength. The wearing strips or rails are directly supported by 90 the beam with only secondary dependence upon the retaining bolts.

It will be apparent that numerous modifications in the construction shown may be made without departing from the spirit of 95 the invention, and I therefore do not wish to be limited to the exact details as shown and described.

Having described my invention what I claim and desire to secure by Letters-Pat- 100 ent is,

1. In an elevated trackway, the combination of a beam having a flange, a rail having a head, the under side of the head being supported by said flange, and means 105 for clamping the rail to the beam.

2. In an elevated trackway, the combination of a headed rail, means for supporting the same comprising a beam having a flange engaging the under side of the head of the 110 rail, and clamping means for holding the beam and rail in operative relation.

3. In an elevated trackway, the combination of a beam having a lateral flange, a rail having an overhanging head, said 115 flange supporting the rail at the under side of the head thereon, and clamping means exterior to the beam for securing the rail and beam together.

4. In an elevated trackway, the combination of a beam having a flange, a rail resting on the flange, and means extending transversely of and beneath said beam for clamping the rail to the beam.

5. In an elevated trackway, the combination of a beam having lateral flanges, headed rails supported by each of said flanges, each rail being supported at the under side of the head thereon, and means for clamping the rails to the beam.

6. In an elevated trackway, the combination of a beam having opposite lateral flanges, rails having heads resting on the flanges and having parts extending beneath the flanges, and common means for clamping the rails to the beam, said means engaging both rails.

7. In an elevated trackway, the combination of a beam having a lateral flange, a headed rail supported by the beam, the under side of the head resting on said flange, said rail having a part extending beneath the flange, and means for clamping the rail to the beam comprising a device which extends beneath the beam.

8. In an elevated trackway, the combination of a beam having a lateral flange, a rail supported by the beam, a spreader engaging the rail to hold the same in proper relation to the beam, and means for clamping the rail to the beam.

9. In an elevated trackway, the combination of a beam having a lateral flange, a headed rail arranged with its head partly above and supported by said flange, a

spreader beneath the flange and engaging the rail, and means for clamping the said parts together.

10. In an elevated trackway, the combination with a beam having a lateral flange, of a rail having a web and a laterally extending head, the head resting on said flange and the web extending below the same, a spreader beneath the beam and in contact with the web of the rail, and a bolt for clamping said parts together.

11. In an elevated trackway, the combination with a beam having upper and lower oppositely extending flanges, rails having heads resting on the lower flanges and webs extending below said flanges, a spreader between said webs, and means for clamping the said parts together.

In testimony whereof I affix my signature in presence of two witnesses.

JAMES A. SHEPARD.
